UNITED STATES PATENT OFFICE.

JOHN MAX CHAMBERS, OF BALTIMORE, MARYLAND, ASSIGNOR TO OLIVER P. LE
COMPTE, OF TOWSON, MARYLAND.

GRIP HANDLE.

1,426,357.

Specification of Letters Patent. Patented Aug. 22, 1922.

Application filed August 5, 1921, Serial No. 490,076. Renewed July 7, 1922. Serial No. 573,456.

To all whom it may concern:

Be it known that I, JOHN MAX CHAMBERS, a citizen of the United States, residing at Baltimore, State of Maryland, have invented 5 a new and useful Grip Handle, of which the following is a specification, and the accompanying drawing, forming a part of the same.

The condition of steel flat bar stock as 10 manufactured for general commercial purposes is known to variate from its nominal size and as this stock is used in a variety of ways, in one instance for door latches, my invention consists of an improvement in 15 grip-handles, wherein I provide means for the reception of these latches, means for the self adjustment to and gripping the bars as they variate from the nominal size and means for a convenient finger purchase on 20 handle to operate same.

I obtain the objects of my invention by the construction shown in the accompanying drawing in which—

Figure 1 is a perspective view showing the 25 front and side elevation. Fig. 2 is an enlarged section on line A—B of Fig. 1.

Referring to the drawing, the numeral 1 is a body in which a socket 3 with the internal face 4 of side walls converging as 30 shown in Fig. 2 for the uniform bearing of

said faces against the flat bar as it is inserted in socket, forcing apart the side walls by reason of channel 5, in face of body 1, permitting the expansion of socket thereby giving a frictional grip on inserted bar as the 35 walls of socket seek their original position. The finger-grip 2 is integral with body 1 and as it extends away from the face of body at its connection to same it terminates inwardly toward the face thereby causing a depression at the change of direction giving a convenient retaining finger-grip. 40

Having described my invention what I claim as new is:—

A grip-handle comprising a body having 45 a socket with the internal face of the side walls converging towards a channel through front wall of body, all for purposes as described and a finger-grip, integral with aforesaid body, having a depression constructed as shown in the accompanying drawing. 50

In testimony whereof, I have signed my name to this specification in the presence of two subscribing witnesses.

JOHN MAX CHAMBERS.
